UNITED STATES PATENT OFFICE.

JOHN DARBY, OF PHILADELPHIA, PENNSYLVANIA, ASSIGNOR TO SHUR LOC ELEVATOR SAFETY CO. INC., OF NEW YORK, N. Y., A CORPORATION OF NEW YORK.

ELEVATOR.

Application filed December 24, 1925. Serial No. 77,441.

This invention relates to elevator mechanism of the general character of that shown in Letters Patent of the United States of Glenn S. Williamson, No. 1,566,713, dated December 22, 1925, in which the power for operating the door of the car or of the elevator shaft, or the doors of both, is supplied by an air compressor in operative relation with some moving part of the elevator mechanism so that it shall be driven when and only when the elevator car is moved and by the same power which moves the elevator car, regardless of the direction of movement of the car, suitable provision being made whereby the doors can be moved in either direction at the will of the operator. Various devices have been proposed heretofore whereby power can be stored during the movement of the car, to be applied at the will of the operator in the movement of the doors, involving for example, the storing of power in a spring or in a weight, but such devices have not proved altogether satisfactory in operation. In the arrangement described in the application above mentioned, an air compressor mounted on the car stores air under compression in a tank from which it is supplied directly to the motor devices by which the door is moved, which arrangement is preferable to those in which power is stored in a spring or in a weight, the operation of which cannot be controlled satisfactorily.

By the present invention it has been sought to overcome such objections as there may be to the actuation of the door operating means directly by compressed air drawn from the receiver in which it is stored by the compressor on the car and in accordance with the present invention provision is made whereby the power means, such as a pump, actuated by the movement of the car, acts upon an incompressible medium, such as oil, and delivers it to an air tank or receiver in which air or some other compressible medium is compressed to a predetermined degree and its pressure is made to actuate the door operating motor so as to cause it to move the door in one direction or the other under the control of the operator. The invention is further concerned with the mechanical devices through which the power of the door operating motor is applied to the door and to the devices through which it is made possible for the operator, in case of

need, to move the door independently of the door operating motor. The invention will be explained more fully hereinafter with reference to the accompanying drawings in which it is illustrated as embodied in a suitable structure and in which:

Figure 1 is a view in elevation, partly broken off, showing a portion of an elevator car equipped with the improved door operating devices, a portion of a shaft door being also shown.

Figure 2 is a diagrammatic view, illustrating more particularly the means whereby the power devices on the car are actuated through the movement of the car.

Figure 3 is a view in elevation, partly broken off, of the parts shown in Figure 1 as seen from the left-hand in said figure.

Figure 4 is a detail view of the four-way valve shown in Figures 1 and 2.

Figure 5 is a view partly in vertical section and partly in elevation, showing particularly the power source on the car and some of its connections.

Figure 6 is a view in elevation of the parts shown in Figure 5 as seen from the left-hand.

Figure 7 is a view in elevation and on a larger scale of the operating connections through which the door motor on the car is made to move the door.

Figure 8 is a view of the same as seen from above.

Figure 9 is a view of the same in elevation as seen from the left-hand in Figure 8.

Figures 10, 11 and 12 are detail views of some parts of the operative connections shown in Figures 7, 8 and 9.

Figures 13 and 14 are detail views in horizontal section and in elevation respectively, of the devices for effecting engagement between the traveller hereinafter referred to and the door.

Figure 15 is a partial view generally similar to Figure 1 but illustrating the application of an automatic control for the door operating motor.

Figure 16 is a diagrammatic view illustrating the construction and arrangement of such an automatic control.

Figure 17 is a detail view of a car controller handle.

In Figure 1 of the drawing there is shown at a portion of the frame or body of an elevator car of ordinary construction, the

floor being indicated at a' . It is assumed that the car is raised or lowered by any usual or suitable means sufficiently indicated at o, o' in Figure 2, since the present invention is not concerned therewith. It is also assumed that the car is provided with a controller box and handle and an interlocking rod which operates in the usual manner to prevent the movement of the controller handle to start the car when the car door or the shaft door is not in closed position. These parts may be of any usual or suitable construction and need not be shown, the present invention not being directly concerned therewith. At each shaft landing there is a suitable door b , which is movable horizontally to open or close the shaft opening through the operation of the devices hereinafter described. This door is shown as of a pivoted lattice construction but obviously may be of any suitable character.

In the embodiment of the invention illustrated in the drawings, particularly in Figure 2, as a suitable means for the operation of the power or pump hereinafter mentioned, a relatively fixed cable c , which may have connected to it at its lower end a weight c' for the purpose of maintaining it under tension, and may have its upper end connected to a relatively fixed point at the top of the elevator shaft, as at c^2 , is passed about sheaves c^3 and c^4 , one of which, in the construction shown, operates a double-acting pump d (secured to the underside of the car floor) through the medium of a crank disc d' , shown in broken lines in Figure 5, to which are connected the pitmen d^2 of two pistons e^3 which reciprocate in corresponding cylinders e^4 . The cylinders are shown as mounted within a tank e^5 , with which each cylinder is connected through a suitable intake valve e^6 . From each cylinder the incompressible medium, such as oil, which is operated upon by this power motor or source of power, is delivered through a suitable outlet valve e^7 and pipe connection e^8 to an air tank or receiver e^9 , in which air, or some other suitable compressible fluid, is compressed by the delivery to the receiver of the incompressible medium supplied by the source of power.

In order that an excessive pressure shall not be developed in the receiver e^9 , there is provided suitable means through which, when the required pressure has been developed in the receiver e^9 , the delivery of the incompressible medium to the receiver e^9 is stopped and the medium is returned directly to the reservoir e^5 , notwithstanding the continued operation of the power source in the movement of the elevator car. As shown, the receiver e^9 is connected by a pipe e^{10} with an ordinary diaphragm pressure regulator e^{11} , the stem e^{12} of which carries a valve e^{13} , which controls the delivery of

the compressible medium through a connection e^{14} into the receiver e^9 and a valve e^{15} which controls the return of the incompressible medium to the reservoir e^5 through a connection e^{16} . A check valve e^{17} may be introduced in the connection e^{14} . As will be understood, development of the predetermined pressure in the receiver e^9 moves the regulator stem e^{12} downward against the pressure of the spring e^{18} , seating the valve e^{13} so as to prevent the further delivery of fluid to the receiver e^9 , and unseating the valve e^{15} so that the fluid is thereby bypassed or short-circuited and returned directly to the tank e^5 .

It will be understood that by the delivery of the oil or other incompressible fluid into the bottom of the receiver e^9 , which is closed at its top, the air in the receiver is compressed therein and that the pressure so developed can be applied to the operation of the elevator doors. This is most conveniently accomplished, in accordance with the present invention, through the medium of the same incompressible fluid by which the pressure is developed. As shown, the oil or other incompressible fluid can be delivered from the lower end of the receiver e^9 through a connection e^{19} and branch connections e^{20}, e^{21} , under the control of a four-way valve of ordinary construction, as shown at e^{22} in Figures 1 and 2 and in detail in Figure 4, to one end or the other of a power cylinder f , which is also mounted on the car. The valve e^{22} is provided with a suitable handle e^{23} , for operation by the operator or conductor and has also a connection e^{24} with the tank e^5 , the construction of the four-way valve being such, as shown in Figure 4, that when connection is made from the receiver e^9 to one or the other of the branches e^{20}, e^{21} , the other branch is connected to the tank e^5 so as to return to the tank the oil which is discharged from the corresponding end of the cylinder f .

As shown in Figures 3 and 9, the rod f' of the piston within the cylinder f carries a rack f^2 which, in the arrangement shown, engages a gear segment f^3 , which carries a bevel gear segment f^4 in engagement with a corresponding bevel segment f^5 , mounted loosely on a shaft f^6 , which is mounted in suitable bearings on the elevator car. A clutch member f^7 , splined on the shaft f^6 so as to rotate therewith but to be capable of longitudinal movement thereon, and provided with pins f^8 for engagement with the bevel gear segment f^5 , provides a means under the control of the operator for effecting operating engagement and disengagement between the bevel gear segment f^5 and the shaft f^6 . As shown, the clutch member f^7 is engaged by a clutch lever f^9 , shown clearly in Figures 3 and 9, which has a pin f^{10} engaged in a cam slot f^{11} formed in a

bracket f^{12} which is carried by a vertical rod f^{13} , held normally in its elevated position through its connection with devices to be described, so that the clutch member f^7 is held normally in engagement with the bevel segment f^5 , and capable of being moved downward to disengage the clutch member and perform another function to be described, through its connection at its lower end to a lever f^{14} , shown in Figures 1 and 3, under control of the operator, through a foot press f^{15} .

Partial rotation of the shaft f^6 , either by the power devices or by the operator as hereinafter described, effects first the engagement of the hereinafter mentioned traveller with the shaft door, and then effects movement of the traveller to open the door.

In the arrangement of the door operating devices shown, through which the movement of the door is effected through operation of the door operating motor represented by the cylinder f , the shaft f^6 has keyed thereon, as shown in Figure 11, a sector g which carries at one point a pin g' engaged by the slotted upper end f^{16} of the rod f^{13} , so that upon downward movement of the rod f^{13} through pressure applied to the foot press f^{15} and lever f^{14} , the sector g and the shaft f^6 will be rocked, while movement of the sector by the power devices can be effected without moving the rod f^{13} . The sector also carries, for a purpose to be explained, a preferably squared pin g^2 . It also is provided

on its opposite side with a lug g^3 which supports a rod g^4 curved in an arc concentric with the sector and the shaft. The rod g^4 serves as a support for the spring g^5 (omitted from Figure 12 to avoid confusion) which abuts at one end against a lug g^3 and at the other end against a lug h on the sector h' which floats or is mounted loosely on the shaft f^6 . In the relative movement of the sectors g and h' , the curved rod g^4 is guided in the lug h , which is perforated for the purpose. The lug h , as shown by broken lines in Figures 7 and 11, is formed at the end of a radial rib h^2 on the corresponding side of the sector h' and the sector g is also provided with a stud g^6 formed with an eccentric g^7 capable of rotation on the stud for the purpose of effecting close adjustment of the point at which, in the movement of the sector g , operative contact between the eccentric g^7 and the rib h^2 , and therefore operative engagement between the sector g and the sector h' , shall be effected. A similar eccentric h^8 , formed on a stud h^4 carried by the sector h' , forms an adjustable stop to limit the closing movement of the sector g with respect to the sector h' . It will now be understood that in the initial movement of the sector g from its normal position of rest, shown in Figure 7, the spring g^5 is at first compressed between

the abutments g^3 and h without producing any movement of the sector h' . The purpose in thus delaying the movement of the sector h' is to permit the sector g , in its initial movement, to effect, through devices to be described, engagement between the traveller hereinafter mentioned and the shaft door. Eventually, however, either through compression of the spring g^5 or through operative engagement effected by contact of the eccentric sleeve g^6 with the rib h^2 of the sector h' , the sector h' is moved by the sector g and continues to be moved throughout the movement of the sector g . The movement of the sector h' on its axis effects, through the devices to be described, the movement of the door.

Supported on the top of the car are rails, i , i' , on which is mounted for horizontal movement a traveller k provided with rollers k' which engage the rails. The traveller k , which is operatively engaged with the door as hereinafter described, has pivotally connected thereto one member k^2 of a toggle lever, the other member k^3 of which is secured to the sector h' , as shown in Figures 8, 11 and 12, whereby, when the sector h' is rocked on its axis, as above explained, the toggle lever is flexed, as indicated by broken lines in Figure 1, and the traveller k is moved from the position shown by full lines in Figure 1 to the position shown by broken lines in the same figure.

As the car comes to rest at any floor or shaft opening, the traveller is not in operative engagement with the shaft door and such engagement must therefore be effected before the door can be opened. The initial movement of the sector g is made to effect such engagement through the devices now to be described. Substantially as shown and described in the application above mentioned, the traveller k is provided with opposed jaws k^4 , mounted to swing on vertical axes, inter-connected, as shown for example at k^5 in Figures 13 and 14, so that they shall move together, and held normally in retracted or inoperative position by coiled springs k^6 . These jaws are adapted to be moved into operative position, as shown by broken lines in Figure 13, to engage between them a bar b' carried by the door b . One of these jaws has an arm k^7 which carries a roller k^8 shown clearly in Figure 13. In the retracted or inoperative position of the jaws k^4 , the roller k^8 rests in a slot l formed in a bar l' which is supported on the car, preferably between the rails i and i' , so as to be capable of limited longitudinal movement. Such movement of the bar l' to the right from its initial position forces the roller k^8 out of the slot l and moves the jaws k^4 from their retracted or inoperative positions to their extended or operative positions, as in

dicated by broken lines in Figure 13. So long as the bar l' remains in its new position, the jaws h^4 will be retained in their extended or working positions, but as soon as the bar l' is permitted to return to its initial position, the roller h^8 will move into the slot l and the jaws h^4 will be returned by the springs h^6 to their retracted or inoperative positions.

18 The bar l' is held normally in its initial position by a coiled spring l^2 which, as shown in Figures 1, 7 and 8, abuts at one end against the frame which supports the tracks i, i' and the bar l' and at its other end against a lug or bracket l^3 on the bar l' . To effect longitudinal movement of the bar l' for the purpose of moving the jaws h^4 to extended or working position, there is pivotally mounted on an arm m , of one of the standards m' which supports the shaft f^6 , a rocker arm n which carries at its lower end a roller n' to bear against the end of the bar l' . At its upper end, above its pivot n^2 , it bears a spring pressed latch n^3 adapted for engagement with the squared pin g^2 of the sector g and provided with an adjusting screw n^4 to limit the movement of the latch. As the radius of the shorter portion of the rocker arm n is considerably less than the radius of the pin g^2 and is non-concentric therewith, it will be seen that while in the initial movement of the sector g the rocker arm will be moved through the engagement of the latch n^3 with the pin g^2 and the bar l' will be moved against the tension of the spring l^2 so as to throw the jaws h^4 into extended or working position, the latch n^3 , in the continued movement of the sector g , will be disengaged from the pin g^2 and the bar l' will be returned to its initial position. This does not take place, however, until the movement of the traveller has commenced, so that during the continued movement of the carrier during the opening movement of the door and also during the closing movement of the door, the roller h^8 will rest against the bar l' and the jaws h^4 will be held thereby in extended or working position until, in the return of the traveller, the door reaches its fully closed position when the roller moves again into the slot l and the jaws are returned by their springs to the retracted or inoperative position.

It will be understood, of course, that the movement of the traveller in the opening of the door and thereafter in the closing of the door is effected by the door operating motor f under the manipulation of the four-way valve e^{22} by the operator. It will also be understood that the movement of the sector g to effect the engagement of the traveller with the shaft door and thereafter to move the shaft door, can be accomplished by the operator through the application of his foot 65 to the foot press f^{15} without operation of

the door operating motor f and also that the slotting of the upper end of the vertical rod f^{13} permits the operation of the door by power without movement of the rod f^{13} and its associated parts.

In the foregoing explanation of the nature of the invention with reference to its embodiment in the construction thus far described, it has been assumed that the door operating motor is controlled by the operator through the manipulation of the valve e^{22} , but it will be obvious that it might be controlled by automatic or semi-automatic devices, the operation of which is initiated by or involved with the movement of the car itself, so that the operation of the door operating motor, to open the door, is effected automatically as the car comes to rest. One form of such automatic devices is illustrated in Figures 15, 16 and 17 and will now be described.

The shaft c^{41} , which carries the sheave c^4 is shown as having a gear c^{42} which meshes with a pinion c^{43} on a governor shaft c^{44} which carries an ordinary governor c^{45} . The longitudinally movable sleeve c^{46} of the governor carries an insulated bridge piece c^{47} which, when the governor is at rest and therefore when the elevator car is stationary, bridges two electrical terminals 5 and 6. When the car is in motion and the governor is rotated, the bridge piece c^{47} is withdrawn from the terminals 5 and 6 and the circuit therethrough is opened.

Positioned in suitable proximity to the governor is a magnet 7, the electrical connections of which will be referred to hereinafter. Associated with the magnet 7 is an armature lever 8 which carries an insulated bridge piece 9 to bridge the gap between two terminals 11 and 12, the armature being held normally in contact with the terminals as by a spring 10. An extension 13 of the armature 8 beyond its pivot is adapted to be engaged by a latch 14 in such operative relation with the governor that when the governor is in motion and the bridge piece c^{47} is withdrawn, the latch disengages the armature extension 13 and permits the armature to be influenced by the magnet 7. A spring 16 holds the latch 14 normally in engagement with a flange on the movable sleeve of the governor.

The stem e^{25} of the door controlling valve e^{22} has fixed thereto an arm 24 which has a pin and slot connection with a lever 21, pivoted at 23. Through a pin and slot connection 20, 22, the lever 21 is operatively connected with the common armature 19 of two solenoids 17 and 18. The lever 21 carries a bridge piece 27 which is adapted, when the lever is in the full line position, to bridge the gap between two terminals 28, 29 and, when the lever is in the dotted line position, to bridge the gap between two terminals 30, 31.

It will be observed that the terminal 6 is connected through the solenoid 17 to the terminal 30 and that terminal 5 is connected through the terminals 11 and 12 and the bridge piece 9 to the positive pole of the battery B, the negative pole of which is connected to the terminal 31, from which the circuit is completed to the terminal 30 by the bridge piece 27 at the proper time.

It will further be observed that the terminal 28 is connected through the winding of the magnet 7 to the negative pole of the battery and that the terminal 29 is connected through the solenoid 18 and the terminals 32, 33 of the button-switch H to the positive pole of the battery.

When the car comes to rest and the movement of the governor ceases, the arm 21 being just previous to that action in the dotted line position, the solenoid 17 is energized and the lever 21 is thrown to the full line position, shifting the valve e^{22} so as to admit pressure to the door operating motor to cause the door to open. This movement of the lever 21, it will be observed, by opening the gap between the terminals 30, 31, breaks the circuit through the solenoid 17, leaving it dead.

To shift the valve e^{22} so as to bring about the closing of the door, the lever 21 must be thrown from the full line position to the dotted line position. To accomplish this the solenoid 18 must be energized and this is effected by a button switch H conveniently located in the car, as for example, in the controller handle, as shown in Figure 17. The operation of this switch closes the circuit from the positive side of the battery through the solenoid 18, and the terminals 29, 28 with the bridge piece 27 to the negative pole of the battery. This movement of the lever 21, by the movement of the bridge piece 27 from the terminals 28, 29, breaks the circuit through the solenoid 18 and in turn leaves it dead, while placing the connections through the solenoid 17 in readiness to have the circuit closed through them by the bridge piece e^{47} .

As the elevator car must not move until the door is closed, the governor will not break the circuit through the solenoid 17, and unless another means is provided to break this circuit, the magnet 17 would again be energized when the lever 21 is moved to the dotted line position and the door would be opened. To prevent this action, the magnet 7 is provided so that when the circuit through the same is closed by the operation of the button switch H, it is energized and the circuit through the solenoid 18 is broken at the gap 11, 12.

The circuit through the solenoid 17 might be kept open until after the movement of the elevator car commences by holding the button switch H in closed position, but to

avoid this necessity the latch 14 is provided, so that when the armature 8 is influenced by the magnet 7 its extension 13 will be engaged by the latch 14 and in this manner the gap 11, 12 will be kept open and the latch is disengaged by the movement of the governor as soon as the movement of the car has commenced, leaving the armature 8 free to be actuated by the spring 10.

In the embodiment of the invention illustrated in Figure 1 and in the description of the construction there shown, the door to be operated is shown and referred to as a shaft door, but the term "door" as used in the claims, unless otherwise specified, is to be understood in a broad sense, as indicating a door of any kind, either as to its particular construction or its location, and either as a shaft door or as a car door.

It will be seen that the pump and the receiver or tank, with the necessary connections, constitute a convenient form of hydro-pneumatic power generating means for the door operating motor and any other form of hydro-pneumatic power generating means, whether operated through the movement of the car or otherwise, might be substituted for the particular form shown as the convenience or preference of the manufacturer or user or the conditions of use might suggest.

Various changes in details of construction and arrangement can be made to suit different conditions of use and the invention, therefore, except as pointed out in the accompanying claims, is not limited to the particular construction and arrangement of parts as shown and described herein.

I claim as my invention:

1. In an elevator, the combination of a door, a reciprocating door operating motor, an air tank, means by which an incompressible medium is forced into the tank to compress the air therein, connections from the tank to opposite sides of the door operating motor to determine the direction of movement thereof by the incompressible medium under the pressure of the air in the tank, and a manually controlled device to determine the delivery of the incompressible medium to one side or the other of the motor.

2. In an elevator, the combination of a door, a door operating motor, an air tank, a pump to force an incompressible medium into the tank to compress the air therein, a connection from the tank to the door operating motor through which the incompressible medium is delivered from the tank under the pressure of the air to the motor to actuate the same, and connections through which the incompressible medium is returned from the tank to the pump.

3. In an elevator, the combination of a door, a door operating motor, an air tank, a pump to force an incompressible medium

into the tank to compress the air therein, a connection from the tank to the door operating motor whereby the pressure in the tank is transmitted to the motor to actuate the same, a connection through which the incompressible medium is short circuited through the pump, and devices controlled by the pressure in the tank to determine the connection of the pump to the tank or the short circuiting of the incompressible medium through the pump.

4. In an elevator, the combination of a door, a door operating motor, an air tank, a pump to force an incompressible medium into the tank to compress the air therein, a connection from the tank to the door operating motor whereby the pressure in the tank is transmitted to the motor to actuate the same, a connection through which the incompressible medium is short circuited through the pump, a valve to determine the delivery of the incompressible medium to the tank or the short circuiting of the same through the pump, and a device subject to the pressure in the tank to shift the valve.

5. In an elevator, the combination of a door, a traveller, a swinging spring retracted jaw carried by the traveller and adapted to engage the door, said jaw having an operating arm, a movable bar mounted in proximity to the path of the movement of the traveller and having a slot for co-operation with said arm, means to operate the traveller, and devices actuated in the initial movement of said means to move the bar and thereby to move the jaw into operative position.

6. In an elevator, the combination of a door, a traveller, normally retracted door engaging devices carried by the traveller, a movable, spring pressed bar mounted in proximity to the path of the traveller and adapted to control the position of the door engaging devices, means to operate the traveller, and devices actuated in the initial movement of said means to move the bar and thereby to move the door engaging devices into operative position.

7. In an elevator, the combination of a door, a traveller, normally retracted door engaging devices carried by the traveller, a movable spring pressed bar mounted in proximity to the path of the traveller and adapted to control the position of the door engaging devices, a sector operatively connected to the traveller, means to oscillate the sector, a rocker arm in operative relation with the bar to move the same, and means whereby the rocker arm is connected in the initial movement of the sector.

8. In an elevator, the combination of a door, a traveller, normally retracted door engaging devices carried by the traveller, a

movable spring pressed bar mounted in proximity to the path of the traveller and adapted to control the position of the door engaging devices, a sector operatively connected to the traveller, means to oscillate the sector, a rocker arm mounted non-concentrically with respect to the sector and in operative relation with the bar to move the same, and a latch carried by the rocker arm and engaged with the sector in the initial movement thereof and disengaged therefrom in the movement of the sector.

9. In an elevator, the combination of a door, a traveller adapted to be connected to the door to move the same, normally retracted door engaging devices carried by the traveller, a sector, means to oscillate the same, a second sector operatively connected to the traveller, connections between the two sectors whereby movement of the second sector is effected in the continued movement of the first sector after its initial movement, and means whereby the door engaging devices are moved to operative position in the initial movement of the first sector.

10. In an elevator, the combination of a car, a door operating traveller mounted on the car, a motor also mounted on the car, operating connections between the motor and the traveller including a clutch, devices mounted on the car and adapted to be actuated by the operator to actuate said connections, and means operated by the movement of said devices to disengage the clutch.

11. In an elevator, the combination of a car, a door operating traveller mounted on the car, a motor also mounted on the car, a rock shaft, operating connections between the motor and the rock shaft and including a clutch, operating connections between the shaft and the traveller, devices mounted on the car and adapted to be actuated by the operator to actuate said last named connections, and means operated by the movement of said devices to disengage the clutch.

12. In an elevator, the combination of a door, a traveller, a swinging spring retracted jaw carried by the traveller and adapted to engage the door, said jaw having an operating arm, a movable bar mounted in proximity to the path of movement of the traveller and having a slot for cooperation with said arm, a toggle lever system having one member connected to the traveller, means to oscillate the other member of the toggle lever system, and devices actuated in the initial movement of said means to move the bar and thereby to move the jaw into operative position.

This specification signed this 23d day of December A. D. 1925.

JOHN DARBY.
